UNITED STATES PATENT OFFICE.

FERDINAND ZIGANEK AND CHARLES W. SCHWAB, OF DETROIT, MICHIGAN.

VENTILATOR.

Application filed October 14, 1922. Serial No. 594,471.

To all whom it may concern:

Be it known that we, FERDINAND ZIGANEK and CHARLES W. SCHWAB, citizens of the United States, residing at Detroit, in the county of Wayne and State of Michigan, have invented certain new and useful Improvements in Ventilators, of which the following is a specification, reference being had to the accompanying drawings.

10 This invention relates to improvements in ventilators, and an important object of the invention is to provide a combined induction and eduction force draft ventilator.

15 A further object of the invention is to provide a construction of this character wherein the ventilating passages for induction and eduction are arranged concentrically.

20 A still further object of the invention is to provide a construction wherein the outward passage of foul air is so controlled and arranged as to prevent the passage into the induction chamber of particles of matter heavier than air, such as dust and the like.

25 Another object of the invention is to provide a construction of this character wherein the eduction opening through which foul air passes is automatically opened upon starting of the fan employed for creating a current of air through such opening, together with means for automatically closing the opening when the fan is stopped.

30 An additional object of the invention is to provide a construction of this character which may be readily assembled, which is adjustable to various thicknesses of walls, and which will be efficient and durable in service, preventing the formation of drafts and the collection of dust and dirt.

35 These and other objects we accomplish by the construction and arrangement shown in the accompanying drawings wherein for the purpose of illustration is shown a preferred embodiment of our invention and wherein like reference characters designate like parts throughout.

In the drawings:—

40 Figure 1 is a sectional view taken through a ventilator constructed in accordance with our invention;

45 Figure 2 is a fragmentary view showing the action of the air currents when the eduction conduit valve is open;

50 Figure 3 is a section on the line 3—3 of Figure 1;

55 Figure 4 is an enlarged sectional view

showing the construction of the induction fan and fan chamber;

60 Figure 5 is a perspective view of a fragment of the fan structure showing the manner of forming the induction and eduction blades;

65 Figure 6 is a sectional view showing the baffle plate employed for actuating the eduction valve;

70 Figure 7 is a plan view of the valve controlling the induction channel; and

75 Figure 8 is a similar view of the manually operated valve controlling the eduction channel.

80 Referring now more particularly to the drawings, the numerals 10 and 11 indicate telescoping tubes adapted to be arranged within an opening 12 formed in a wall W, the outer ends of the tubes being provided with flanges 13 and 14 respectively, these flanges being adapted to embrace the wall within which the tubes are arranged. Securing elements 15 extend through the wall and through the flange 13 of the tube 10. From the inner face of the wall a tube 16 is entered, having at its inner end a flange 17 adapted to abut against the flange 14 of the tube 11. To this tube 16 at the outer end thereof is secured an annular ring member 18, substantially U-shaped in cross section, one arm 19 of the U having engagement with the outer end of the tube. The bight portion 20 of the ring member 18 has openings 20^a formed therein for a purpose presently to appear.

85 A conduit 21 is provided, the inner end of which is slightly offset to form an enlargement at 22, the inner extremity of the tube being provided with an outstanding flange 23, the periphery of which abuts the inner face of the tube 16 and is secured thereto at a point spaced inwardly of the inner end of the tube 16, as indicated at 24. The flange 23 has openings 25 formed therein for a purpose presently to appear.

90 An annulus 26 abuts the inner face of the flange 23 and has openings 27 formed therein corresponding to the openings 25 of the flange 23. By rotating this annulus, the spaces between the openings 27 may be caused to cover the openings 25 and accordingly passage of air there-through prevented. At its lower edge the annulus 26 has secured thereto a handle member 28 having a portion slidably fitting against the inner wall of the tube 16 and 110

an annular portion slidably abutting the face of the flange 17 and to the extremity of which is secured an operating handle 29 of any suitable construction.

6 A tube 30 slidably fits in the inner end of the tube 16 and has its inner end or that end projecting through the inner face of the wall W flared, as indicated at 31, and extending outwardly over the flange 17 of the tube 16, 10 as indicated at 32. The extremity of this extended portion is provided with a flange 33 adapted to abut the wall and fit the outer edges of the flanges 17 and 14. The tube 30 is cut away at those portions wherein the 15 handle member 28 operates to permit movement of the handle, and this tube forms the outer wall of the inner end of the induction passage of the ventilator.

In the enlarged portion 22 of the conduit 20 21 seats the outer end of a second conduit 34, the inner end of which is flared, as indicated at 35. This conduit 34 forms the inner end of the eduction conduit and likewise serves to form the inner wall of the inner end of the induction conduit. Attention 25 is directed to the fact that due to the flaring of the end of the tube 30 and the conduit 34, incoming air will be directed in a plane substantially at right angles to its direction 30 of entrance and will parallel the wall in which the ventilator is placed, thereby preventing the formation of drafts by the incoming air.

The annulus 36 is secured against the 35 flange 13 of the member 10 by means of the securing elements 15 hereinbefore mentioned and is provided adjacent its inner edge with a series of circumferentially arranged openings 37 for the passage of air. The outer 40 edge of the annulus 36 is provided with an outstanding flange 38 for a purpose presently to appear. The central opening 39 of this annulus slidably receives a conduit 40 forming the outer end of the eduction conduit and, as will hereinafter more fully appear, the inner wall of the outer end of the induction conduit. The inner end of the conduit 40 fits within and against the inner face of the ring member 18 and has its inner 45 extremity in slightly spaced relation to the outer extremity of the conduit 21 so as to afford therebetween a slot 41. Arranged within the conduit 21 is a spider 42 forming a support for a motor 43, the shaft 44 of which is co-axial with the conduit 21 and accordingly with the tube 16. It will be 50 noted that between the ring member 18 and the flange 23 of the conduit 21 and between the conduits 40 and 21 and the tube 16 an 55 annular chamber C is formed which communicates with the interior of the conduit 21 through the slot 41. The shaft 44 of the motor has secured thereto, as by means of bushing 45 and lock nut 46, a fan structure 60 comprising blades 47 each of which is pro-

vided at its periphery with an extension 47 directed through the slot 41. Mounted within the chamber C is an annulus 48 substantially U-shaped in cross section, and having the bight portion 49 thereof extending transversely of the chamber C. The extensions of the blades 47 are integrally secured to the inner arm of the annulus 48, thus bracing the blades 47, and the bight portion of the annulus has struck out portions 49^a and 49^b 75 which are oppositely directed and which combine to form fan blades causing a current of air through the chamber C when the fan is rotated in a direction opposite to the path of movement of air under influence of 80 the blades 47. It will accordingly be seen that during operation of the motor a current will be forced outwardly through the conduits 34, 21 and 40 and inwardly through the openings 37, 20^a, 25 and 27, passing into 85 the room being ventilated between the conduit 34 and tube 30 and being directed along the wall of the room, as hereinbefore described.

It has been found in practice that shielding the entrance end of induction conduits is necessary to prevent the collection and entrance to the room of dust and dirt, and to this end we provide upon the exterior of the conduit 40 at that portion thereof which projects beyond the outer face of the wall W, a succession of bells 50, 51 and 52, each of which is dished and has the dished side thereof directed toward the wall W. The innermost bell 52 is formed by employing a 100 disk 53 having a tubular flange 54 connected with the outer edge thereof by a curved wall, the curve of this wall being such as to direct air striking thereagainst into the bells 50 and 51. The conduit 40 has formed therein 105 between the bells 50 and 51 and between the bells 51 and 52, a series of openings 55 each provided at that edge thereof next adjacent the fan with a cowl 56 extending into the 110 conduit.

It will be seen that when the fan is in operation, the passage of air through the conduit 40 will cause a suction to be created at the openings 55, causing a current of air to enter between the bells 50, 51 and 52 and accordingly the air deflected into these bells by the curved surface of the bell 52 to be drawn through the openings 55 and forced from the discharge end of the conduit 40. This movement of the air will tend to withdraw from that air passing in at the induction openings any heavier particles, causing the same to be discharged without the wall together with the vitiated air withdrawn from the room being ventilated. This is due 120 to the fact that the suction caused at the openings between the bells is sufficient to partially counterbalance the suction created between the bell 52 and the flange 38 of the annulus 36 and permit these heavier par- 125 130

ties to fall until they pass out of the current of air moving to the induction opening.

The outer end of the conduit 40 is flared, as indicated at 57, and has seated therein a valve 58, frustro-conical in form and having its inner end entirely closed. To this inner end centrally thereof a shaft 59 is secured, which slidably extends through bearings 60 carried by a suitable support 61 arranged within the conduit 40. Pivoted to the support 61 are bell crank levers 62, the upper ends of one pair of arms of which are diverged and have secured therebetween a baffle plate 64. Between the bearings 60 which are two in number, the arms 63 have a pin and slot engagement with the shaft 59 so that movement of these arms causes a movement of the shaft and a corresponding movement of the 10 frustro-conical valve 58. The outer bearing 60 has abutted thereagainst one end of a coil spring 65 which surrounds the shaft 59, the purpose of which will presently appear. The other arms 66 of the bell cranks 62 have secured to the extremities thereof counterbalance weights 67 of sufficient weight to normally maintain the valve 58 in closed position.

In the operation of the device when the fan is started, a current of air is formed through the induction channel entering the room and a second current which is outwardly directed through the exhaust channel. This second current of air impinging against the baffle plate 64, forces the baffle plate toward the exhaust end of the conduit, causing the shaft to be shifted in its bearings and the valve 58 to open to permit the exhaust of the air. Attention is directed to the fact that the arrangement of the valve 58 is such that upon opening, a current of air is formed along the walls of the conduit 40 increasing the suction at the openings 55 and preventing the collection of dust upon the walls thereof. When the valve 58 is fully opened, the spring 65 is compressed and accordingly when the fan is stopped this spring imparts an initial impulse to the shaft 59 through the arms 63. The closing of the valve 58 is completed by the counter-weights 67 and the valve maintained normally in closed position by these counterweights.

To prevent the collection of dust upon the walls of the conduits 34 and 21, we provide an adjusting member 68 in the form of a disk having its inner face dished centrally and provided at its periphery with a flange adapted to engage about the outer edge of the bell 35 of the tube 34. This disk has formed therein a plurality of radially extending openings 69 increasing in width toward their outer ends so that incoming air is directed largely against the walls of the conduits 34 and 21 and the col-

lection of dirt thereby prevented. Furthermore this construction has been found to greatly assist in the elimination of drafts at the induction end of the exhaust. Upon the inner face of the dished portion of the disk 68 we arrange a dished control member 70, the position of which is controlled by an operating member 71 extending through the disk 68 centrally thereof and which control member is provided with openings similar to the openings 59 of the disk 68. These openings are sufficiently spaced to permit complete covering thereof by the spaces intermediate the openings so that the exhausting of air from the room being ventilated may be discontinued at any time.

From the foregoing it is believed to be obvious that by the use of a ventilator constructed in accordance with our invention the formation of drafts is to a great extent avoided, and the induction to a ventilated room of dust and dirt to a great measure prevented. It will also be noted that the automatic control of the eduction end of the eduction conduit will tend to prevent the formation of back drafts when the ventilator is not in use and the entrance of wind and rain. Many changes being possible in the construction hereinbefore set forth without in any manner departing from the spirit of our invention, we do not limit ourselves to the specific structure thereof, except as hereinafter claimed.

We claim:—

1. In a ventilator, a conduit, means surrounding the conduit and combining therewith to form about the conduit an annular passage, the wall of the conduit having a slot extending therethrough and affording communication with said passage, a fan structure arranged within the conduit, means for rotating said fan structure, and extensions carried by said fan structure extending through the slot of the conduit and provided within said annular passage with blades oppositely pitched from the blades of the fan structure.

2. In a ventilator, a conduit, means surrounding the conduit and combining therewith to form about the conduit an annular passage, the wall of the conduit having a slot extending therethrough and affording communication with said passage, a fan structure arranged within the conduit and embodying blades adapted upon rotation of the fan to cause movement of air through the conduit in one direction, means for rotating said fan structure, an annulus rotatably mounted within said annular passage and integrally connected with the blades of the fan structure by means extending through said slot, said annulus embodying portions forming blades causing a current of air during rotation of the fan.

and within said annular passage in a direction opposite to the direction of movement of the air within the conduit.

3. In a ventilator, a conduit for the passage of air, a valve closing the outlet end of the conduit, means for producing a forced draft within the conduit and toward said outlet end, draft operated means for opening said valve, automatic means for closing said valve, including a shaft upon which the valve is mounted, bearings slidably receiving said shaft, and means engaging the shaft for moving said shaft in a direction to close the valve, operative upon cessation of draft within the conduit.

4. In a ventilator, a conduit for the passage of air, a valve closing the outlet end of the conduit, means for producing a forced draft within the conduit and toward said outlet end, draft operated means for opening said valve, automatic means for closing said valve, including a shaft to which the valve is secured, bearings within the conduit for the shaft, a bell crank lever pivotally mounted within the conduit and having a baffle plate connected therewith upon one arm thereof and provided upon the other arm with a counter-weight, and a connection between said shaft and bell crank lever causing longitudinal movement of the shaft upon pivotal movement of the bell crank lever.

5. In a ventilator, a conduit for the passage of air, a valve closing the outlet end of the conduit, means for producing a forced draft within the conduit and toward said outlet end, draft operated means for opening said valve, automatic means for closing said valve, including a support within the conduit, bearings carried by the support, a shaft slidably mounted in the bearings and to which said valve is secured, bell crank levers mounted upon opposite sides of said support and having corresponding arms thereof provided with a pin and slot engagement with said shaft, and a baffle plate carried by said arms and arranged in the path of movement of air passing through the conduit, the other arms of said levers being provided with counter-weights.

6. In a ventilator, a conduit for the passage of air, a valve closing the outlet end of the conduit, means for producing a forced draft within the conduit and toward said outlet end, draft operated means for opening said valve, automatic means for closing said valve, including a support within the conduit, bearings carried by the support, a shaft slidably mounted in the bearings and to which said valve is secured, bell crank levers mounted upon opposite sides of said support and having corresponding arms thereof provided with a pin and slot engagement with said shaft, a baffle plate carried by said arms and arranged in the path

of movement of air passing through the conduit, the other arms of said levers being provided with counter-weights, the pin and slot engagement of said arms with said shaft being intermediate said bearings, and a spring surrounding said shaft intermediate said arms and the bearing of the shaft remote from said means for producing a forced draft in the conduit.

7. In a combined induction and eduction ventilator, telescopic tubes adapted for arrangement within a wall opening, a sectional conduit arranged concentrically with said telescopic tubes and combining therewith to form an annular chamber surrounding the conduit, a flange formed on one of the sections of said conduit and engaging against the inner face of one of said tubes to maintain said conduit in spaced relation to said tubes, said flange being provided with draft openings, an annular valve plate abutting said flange and likewise provided with draft openings, means for rotating said plate and means for maintaining said plate in position against said flange.

8. In a combined induction and eduction ventilator, telescopic tubes adapted for arrangement within a wall opening, a sectional conduit arranged concentrically with said telescopic tubes and combining therewith to form an annular chamber surrounding the conduit, a flange formed on one of the sections of said conduit and engaging against the inner face of one of said tubes to maintain said conduit in spaced relation to said tubes, said flange being provided with draft openings, an annular valve plate abutting said flange and likewise provided with draft openings, means for rotating said plate, and means for maintaining said plate in position against said flange, including a flared tube engageable with the interior of the tube against which said flange abuts and having its inner end abutting said plate.

9. In a combined induction and eduction ventilator, telescopic tubes adapted for arrangement within a wall opening, a sectional conduit arranged concentrically with said telescopic tubes and combining therewith to form an annular chamber surrounding the conduit, a flange formed on one of the sections of said conduit and engaging against the inner face of one of said tubes to maintain said conduit in spaced relation to said tubes, said flange being provided with draft openings, an annular valve plate abutting said flange and likewise provided with draft openings, means for rotating said plate, and means for maintaining said plate in position against said flange, including a flared tube engageable with the interior of the tube against which said flange abuts and having its inner end abutting said plate, the inner end of the conduit having a flared end combining with said flared tube to

direct draft passing through said opening at right angles to the axis of the conduit and away from said conduit.

10. In a ventilator, an eduction conduit, 5 an induction conduit surrounding and concentric with the eduction conduit, a plurality of bell shaped elements mounted upon the eduction end of the eduction conduit and having their concave faces directed toward 10 the induction end of the induction conduit, the bell next adjacent the induction end of the induction conduit being provided at the edge thereof remote from the induction conduit and at its outer surface with a curved 15 face directing air current away from the induction conduit and into the concave faces of said bells, means for causing a draft within the eduction conduit toward the eduction end thereof, and openings formed in the 20 wall of the eduction conduit intermediate said bells wherethrough exterior air may be drawn.

11. In a ventilator, an eduction conduit, 25 an induction conduit surrounding and concentric with the eduction conduit, a plurality of bell shaped elements mounted upon the eduction end of the eduction conduit and having their concave faces directed toward the induction end of the induction conduit, 30 the bell next adjacent the induction end of the induction conduit being provided at the edge thereof remote from the induction conduit and at its outer surface with a curved face directing air current away from the induction conduit and into the concave faces of said bells, means for causing a draft within the eduction conduit toward the eduction end thereof, and openings formed in the 35 wall of the eduction conduit intermediate said bells wherethrough exterior air may be drawn, said eduction conduit being provided at the eduction end thereof with means directing said draft along the walls thereof, said openings being provided 40 at the edges thereof next adjacent the draft forming means with protecting cowls.

12. In a combined induction and eduction ventilator, telescopic tubes adapted for engagement in a wall opening, a conduit concentrically arranged with said tubes and 45 having a flange maintaining the same in

spaced relation with relation to the tubes whereby to form between the tubes and the conduit an annular induction passage, a motor supported within the conduit and 55 having a shaft, a fan structure carried by the motor shaft and embodying blades forming a current of air in one direction through the eduction conduit, a slot formed in the wall of the conduit and aligned with said 60 blades, said blades having extensions directed through said slot, an annulus disposed within the induction chamber and integrally connected with said extensions, said annulus having a wall extending across 65 the induction chamber, the wall having openings formed therein, the metal removed in forming said openings being attached to the annulus at the edges of the openings and formed to provide blades forming a 70 draft within the induction chamber in a direction opposite to the direction formed by the first named blades in the eduction chamber.

13. In a ventilator, a conduit, means surrounding the conduit and combining therewith to form about the conduit an annular passage, and a fan associated with the conduit and passage including blades operated upon a rotation of the fan structure to 75 produce a draft in one direction through the conduit and in the opposite direction through the annular passage.

14. In a ventilator, a conduit, means surrounding the conduit and combining therewith to form about the conduit an annular passage, and a fan associated with the conduit and passage including blades operated upon a rotation of the fan structure to produce a draft in one direction through 80 the conduit and in the opposite direction through the annular passage, and valves controlling said conduit and passage.

15. In a ventilator, concentric eduction and induction passages, and a fan common 85 to both of said passages and producing by its operation a forced draft in each thereof.

In testimony whereof we hereunto affix our signatures.

FERDINAND ZIGANEK.
CHARLES W. SCHWAB.
